ATTORNEY

UNITED STATES PATENT OFFICE.

JACOB H. BODINGER, OF NEW YORK, N. Y.

STEAM-BOILER.

1,144,995.

Specification of Letters Patent.

Patented July 6, 1915.

Application filed December 9, 1914. Serial No. 876,229.

To all whom it may concern:

Be it known that I, JACOB H. BODINGER, a citizen of the United States, and a resident of New York, borough of Manhattan, in the county of New York and State of New York, have made and invented certain new and useful Improvements in Steam-Boilers, of which the following is a specification.

My invention relates to an improvement 10 in steam boilers, and more particularly to that kind or type thereof used in connection with devices or apparatus for pressing clothes. In boilers of this kind, it is usual to attach to the same a small hand-pump 15 whereby to force the feed water into the boiler, either from a bucket or other vessel, or from the city main, the pressure in the latter often being insufficient to force the water into the boiler against the head or 20 pressure of steam carried therein.

The object of my invention is to construct the main boiler with an auxiliary tank or boiler, and after equalizing the steam therein, to feed the main boiler by gravity from 25 the superimposed auxiliary tank, the latter being supplied with water from the city main during the time when no steam is contained therein.

With this and other ends in view, the invention consists in certain novel features of construction and combinations of parts as will be hereinafter fully described and pointed out in the claims.

In the accompanying drawings, Figure 1 35 is a view in elevation of a boiler constructed in accordance with my invention, parts or portions of the outer and boiler casings being broken away for the sake of clearness. Fig. 2 is a sectional view taken on the line 40 2—2 of Fig. 1, looking in the direction as indicated by the arrow.

Referring to the drawings, it will be seen 45 that my improved boiler comprises an outer casing 3 supported over and on a base 4 in which is contained a gas or other burner 5, supplied with fuel through the inlet pipe 6. Within this outer casing 3 is contained the main boiler 7, provided, as usual, with a number of tubes 8 through which the gases, 50 and products of combustion, flow. Within this casing 3 is also contained an auxiliary tank or boiler 9, a space 10 being preferably left between the upper end of the main boiler 7 and the lower end of the auxiliary tank 9, 55 said tank being also provided with a number of tubes 11 through which flow the heated

gases after passing through the tubes 8, these heated gases and products of combustion entering the chamber 12 and then passing out through the flue or opening 13 formed in the cover or top of the casing 3. Into the lower end of the auxiliary tank 9 leads a water inlet pipe 14 provided with a valve 15 near its upper end and a valve 16 near its lower end, this inlet pipe 14 being 60 preferably connected to the city main, or to a suitable source of water supply under pressure. To the lower side of the main boiler 7 leads a branch inlet 17 provided with a check valve 18 whereby to permit the water 65 in the auxiliary tank 9 to flow down the inlet pipe 14 and through the branch 17 into the main tank 7, the check valve 18 preventing any backflow. From the upper end of the main tank 7 leads the steam outlet pipe 70 19 connecting with the pipe 20, which latter leads into the upper end of the auxiliary tank 9, said pipe 20 being provided with the valve 21 and steam-gage 22, a pipe 23 provided on the valve 24 conveying the steam 75 to the place where the same is to be utilized. The lower end of the pipe 20 leads into the upper end of a header 25, from the lower end of which leads the pipe 26 into the lower end of the main boiler 7, the latter being 80 provided with the gage-glass 27, and the auxiliary tank with the gage-glass 28.

When it is desired to feed or supply the main boiler 7 with water, presuming that the auxiliary tank 9 is filled, or partially 85 filled, it is simply necessary to open the valve 21 in the steam pipe 20, and the valve 15 in the supply pipe 14, the valve 24 in the pipe 23 being closed, as well as the valve 16 in the inlet pipe. Upon opening the valve 21 in the 90 steam pipe 20, the steam in the upper portion of the main boiler 7 will flow through the pipe 19 and pipe 20 into the auxiliary tank 9, thereby equalizing the steam pressure therein. The water contained within 100 the tank 9 will then flow by gravity through the pipe 14 and branch 17 into the lower end of the main boiler 7, the water being permitted to feed therein until the boiler is sufficiently full, whereupon the valves 21 and 24 105 may be opened, and the valve 15 closed. Any condensation of the steam in the pipe 20 will drip into the header 25, out of which it will flow into the bottom of the main boiler. The steam contained in the auxiliary 110 tank and supplied from the main boiler 7 during the operation of filling the latter,

will, in the course of a short while, condense, the pressure in the tank being thereby relieved.

When it is desired to charge the tank 9 with water, it is simply necessary to open the valves 15 and 16, whereupon the pressure in the main will force the water through the inlet pipe 14 into the lower end of the tank 9, the pressure in the main boiler 7 preventing the water from flowing through the branch 17 and into said main boiler, the check valve 18 preventing the pressure in the boiler from forcing the water out of the same and back into the inlet pipe 14. In order to permit of the entrance of the air into the tank 9 as the water is fed therefrom into the main boiler 7, and also during the condensation of the steam in said auxiliary tank; I provide the upper end thereof with a valve 29.

From the foregoing it will be understood that my boiler is simple in construction, easily and readily operated by unskilled persons, and by reason of its construction and arrangement, avoids the necessity of using a force chamber whereby to feed the water into the main boiler; furthermore, the water in the auxiliary tank, by reason of the location of the latter over and above the main boiler, will be partially heated by the gases and products of combustion flowing through and around said auxiliary tank prior to its escape from the outer casing, thus utilizing the heat which has heretofore been wasted, and avoiding the lowering of the temperature of the water in the main boiler to that extent as when cold water is fed into the same directly from the street main.

It will of course be understood that many variations or alterations may be made in the detailed construction of the boiler as shown in the drawings, that is, in regard to the arrangement of piping, the number of tubes contained in the main and auxiliary boilers, etc., and hence I do not limit myself to the exact construction and arrangement shown, the gist of the invention lying in the employment of a main boiler and a superimposed auxiliary tank so connected up as to permit, at desired times, of the equalization of the steam in the two vessels, and the feeding by gravity of water from the auxiliary tank into the main or lower boiler, and

Therefore what I claim is:—

1. A boiler comprising a main boiler, an auxiliary tank located above said main boiler, a water inlet pipe communicating with the lower end of said main boiler and

auxiliary tank, and a steam outlet pipe communicating with the upper ends of said main boiler and auxiliary tank adapted to equalize the pressures therein, and valves located in said pipes.

2. A boiler comprising an outer casing, a main boiler located within the lower portion of said casing and an auxiliary tank located within the upper part of said casing and above said main boiler, an inlet pipe leading into said auxiliary tank and into the lower end of said main boiler, and a steam pipe leading from the top of said main boiler and communicating with the top of said auxiliary tank, and suitable valves located in said pipes.

3. A steam boiler comprising an outer casing containing in the lower end thereof a heating device, a main boiler located within the lower portion of said outer casing, an auxiliary tank located within the upper portion of said outer casing, an inlet pipe connected with any suitable source of water supply under pressure, and connected with the lower ends of said main boiler and auxiliary tank, valves located in said inlet pipe for permitting of the flow of water into said main boiler and auxiliary tank and preventing the flow of water out of said main boiler, a steam outlet pipe leading from the upper end of said main boiler and communicating with the upper end of said auxiliary tank, and valves located in said steam pipe whereby to close the communication between said boiler and auxiliary tank.

4. An apparatus of the class described, comprising a main boiler, an auxiliary tank located above said main boiler, a water inlet pipe communicating with said auxiliary tank, and provided with a valve therein, a pipe communicating with said water inlet pipe and with said main boiler and provided with a check valve therein preventing the flow of water out of said main boiler, a steam outlet pipe communicating with the upper ends of said main boiler and auxiliary tank and adapted to equalize the pressures therein, and valves located in said steam outlet pipe.

Signed at New York, borough of Manhattan, in the county of New York and State of New York, this 8th day of December, A. D. 1914.

JACOB H. BODINGER.
